[57] CLAIM

The ornamental design for a golf training mat, as shown and described.

DESCRIPTION

FIG. 1 is a perspective view of our new design for a golf training mat for a golfer whose arms, club and golf balls are shown in phantom line;

FIG. 2 is a top elevational view of our design;

FIG. 3 is a right side elevational view of our design;

FIG. 4 is a front elevational view of our design;

FIG. 5 is a rear elevational view of our design;

FIG. 6 is a left side elevational view of our design for a golf training mat; and,

FIG. 7 is a bottom elevation view of our design.

The broken line showing of the golf ball is for illustrative purposes only and forms no part of the claimed design.
